UNITED STATES PATENT OFFICE.

WALTER J. FRINK, OF CHATTANOOGA, TENNESSEE.

ADJUSTABLE FRICTION-HOLDING APPLIANCE.

Application filed November 20, 1922. Serial No. 601,957.

To all whom it may concern:

Be it known that I, WALTER J. FRINK, a citizen of the United States, residing at Chattanooga, Hamilton County, and State 5 of Tennessee, have invented certain new and useful Improvements in Adjustable Friction-Holding Appliances, of which the following is a specification.

The present invention relates to friction 10 clamps or locking devices for association with windows and the like, such as basement or casement windows, whereby they may be frictionally held or maintained in any desired position, the appliance permitting 15 ready adjustment thereof for modification or change of such position.

In its preferred embodiment, the invention comprises the use of a rod pivotally fastened to the hinged member, such as the 20 window, to be held in place, which is encircled by a coiled spring having an end pivotally attached to the casement or frame in which the window is mounted, and which has a normal bias or tendency to bend longitudinally into a curved form, so that when 25 it is held straight by the rod around which it is coiled, it will frictionally grasp the rod and hold it from sliding therethrough except when such friction is intentionally 30 overcome by forcing the rod through such elastic retainer when it is desired to change the position of the window.

In order to reinforce such spring it is 35 conveniently enclosed or encased in a metal shell or casing likewise hinged to the casing.

Such shell or tube removes undue strain 40 from the spring when it is swung sidewise during the indicated adjustment, and its employment, in some cases at least, permits the use of a spring of a smaller gauge of wire 45 than would be feasible if the shell were omitted.

The improved device is particularly, but 50 not restrictedly, adapted for use in connection with cellar or basement windows hinged at their tops, but, of course, it has many other desirable and efficient uses in similar relations.

To enable those skilled in this art to have 55 a full and complete understanding of the invention and its several structural and functional advantages, in the accompanying drawing forming a part of this specification and throughout the several views of

which like reference characters have been used to designate the same parts, I have illustrated a common embodiment of the invention, which is presented by way of example only, since the invention is susceptible of a variety of embodiments differing 60 more or less in mechanical details but all including the benefits and advantages incident to the employment of the invention in any of its several forms.

In this drawing: 65

Figure 1 is a vertical section through a vertically disposed window hinged at its top to its frame, the window and frame being equipped with one of the improved and novel holding or locking appliances, such 70 view in dotted lines showing the window part way open;

Figure 2 is a fragmentary face view or elevation of the structure shown in Figure 1;

Figure 3 is an enlarged longitudinal section through the friction holding device;

Figure 4 is a face view of the spring forming a part of the lock shown in Figures 1 and 2; and

Figure 5 is a side view of the same spring showing its natural or inherent tendency to bend or curve laterally.

Referring to these views of the drawing, it will be perceived that there has been 85 shown a part of the window-casing 11 in association with the window 12 hinged at its top edge to the casing at 13 so that it may be swung up to open position or turned down into fully closed position, the window 90 being depicted in an intermediate part-open position in dotted lines and in closed relation in full lines.

A cylindrical metal rod 14, having a bent end forming a stop 15, is pivotally connected 95 at its other end at 16 to a suitable bracket 17 mounted on the hinged frame of the window between its edge equipped with the hinges and its opposite free edge.

A coiled wire spring 18 having a normal or natural tendency or bias to curve or bend laterally, as shown in Figure 5, has an end portion shaped to form a small loop or eye 19, the main coiled part of the spring encircling or encasing the rod 14 which it 105 frictionally grasps, the rod holding the spring substantially straight as seen in Figures 1, 2 and 3.

The attempt of the coils of the spring to bend transversely of the length of the 110

spring as a whole causes an effective frictional grasp thereof on the rod extended through it.

A sheet-metal shell or sleeve 20 encloses or houses the spring and a screw 21 pivotally attaches an extension 22 of the sleeve and the loop 19 of the spring to the window-casing.

As the window is swung on its hinges, 10 the associated elements 18 and 20 rock correspondingly on their hinge mounting 21 and the rod slides through the clamping and grasping coils of the spring.

The turns or loops of the spring have a 15 sufficient frictional hold on the rod so that they will maintain the window fixedly and firmly in any desired position or degree of opening, but, nevertheless, they permit the ready adjustment of the window to new positions by merely temporarily overcoming 20 the frictional hold of the spring on the rod by sliding the latter through the former as the position of the window is changed or varied.

25 If the spring is made of a wire of sufficient cross-section, the outer sleeve or tube may be dispensed with, but its use permits the employment of a spring of wire of less size than would otherwise be feasible because it assumes much of the side strains which would be imposed on the spring if the latter were used alone.

In other words, the sleeve or shell reinforces the spring and protects it against undue or excessive strains due to its rocking or swinging around its pivotal mounting.

The bent end 15 of the rod precludes complete withdrawal of the latter from the spring and hence there is no danger of unintentional separation of these parts.

The invention is capable of incorporation in physical form in several ways and all of such different structures will include the structural and functional advantages arising out of the use thereof. Consequently, 45 the invention is not limited and restricted to the precise and exact details shown and described.

I claim:

50 1. In an adjustable friction holding appliance of the character described, the combination of a coiled spring having a normal

tendency to bend laterally and adapted to be secured to one of two members hinged together, and a rod designed to be secured 55 to the other of said members and extended through the coils of said spring and of a shape different from the normal form of the spring, whereby the latter frictionally grasps such rod but permits its longitudinal sliding therethrough for adjustment.

2. In an adjustable friction holding appliance of the character described, the combination of a coiled spring, means to attach said spring to one of two members hinged 65 together, a rod, and means to attach said rod to the other of said members, said rod extending through the coils of said spring and frictionally held against longitudinal movement in the spring by direct contact 70 with the coils of the spring.

3. In an adjustable friction holding appliance of the character described, the combination of a coiled helical spring having a normal tendency to bend laterally and 75 constructed for pivotal attachment to one of two members hinged together, a rod extended through the coils of said spring and of a shape different from the normal form of the spring whereby the coils of the latter 80 frictionally grasp the rod, said rod being constructed for pivotal attachment to the other of said members, and means to reinforce said spring.

4. In an adjustable friction holding appliance of the character described, the combination of a helical spring having an end 85 formed for pivotal attachment to one of two members hinged together, said spring having a normal tendency to bend laterally, 90 a reinforcing shell enclosing said spring and having an end portion formed for pivotal attachment to the same member, and a rod extended and slidably through the coils of said spring and of a shape different from the normal form of the spring, 95 whereby the coils of the spring frictionally engage said rod, the latter being constructed for pivotal attachment to the other of said members.

In witness whereof I have hereunto set my hand and seal.

WALTER J. FRINK. [L.S.]
